UNITED STATES PATENT OFFICE

147,178

DESIGN FOR A LOCOMOTIVE BODY

Edward J. Harley, Philadelphia, and Lewis W.
Metzger, Doylestown, Pa.

Application January 8, 1946, Serial No. 125,352

Term of patent 3½ years

(Cl. D66—1)

To all whom it may concern:

Be it known that we, Edward J. Harley, a citizen of the United States, residing at Philadelphia, county of Philadelphia, and State of Pennsylvania, and Lewis W. Metzger, a citizen of the United States, residing at Doylestown, county of Bucks, and State of Pennsylvania, have invented a new, original, and ornamental Design for a Locomotive Body, of which the following is a specification, reference being made to the accompanying drawing, forming a part thereof.

In the drawing:

Fig. 1 is a front perspective view of a locomotive body showing my new design;

Fig. 2 is a side elevational view of the front end portion thereof;

Fig. 3 is a top plan view of the portion shown in Fig. 2; and

Fig. 4 is a front elevational view thereof, the other side of the design being similar to that shown in Fig. 1.

We claim:

The ornamental design for a locomotive body, substantially as shown and described.

EDWARD J. HARLEY,
LEWIS W. METZGER.
